UNITED STATES PATENT OFFICE.

TAUBE DAVIS, OF NEW YORK, N. Y., ASSIGNOR TO FRANKLIN SIMON & CO., INC., OF NEW YORK, N. Y., A CORPORATION OF NEW YORK.

DESIGN FOR A DRESS.

Application filed January 16, 1926. Serial No. 16,134. Term of patent 3½ years.

To all whom it may concern:

Be it known that I, TAUBE DAVIS, a citizen of the United States, and a resident of the city of New York, borough of Manhattan, in the county and State of New York, have invented a new, original, and ornamental Design for Dress, of which the following is a specification, reference being had to the accompanying drawing, forming part thereof, wherein the dress is distinguished by means of an ornamental arrangement of diamond-shaped members near the lower edge of the tunic, by similar-shaped ornamental members on each sleeve at the lower end, and the provision of a substantially ornamental diamond-shaped member at the extreme lower end of each sleeve, matching in appearance with a tie, part of

the collar, and part of a pair of hanging straps depending from the adjacent collar.

Figure 1 is a front view of a dress, showing my new design, the same being illustrated on a figure.

Figure 2 is an enlarged side view of the lower part of one of the sleeves of the dress shown in Figure 1.

Figure 3 is an enlarged fragmentary view showing part of the lower section of the tunic illustrated in Figure 1, said view disclosing the ornamental appearance of the diamond-shaped figures.

I claim:

The ornamental design for a dress, substantially as shown and described.

TAUBE DAVIS.
